UNITED STATES PATENT OFFICE.

JAMES T. ROBB, OF BAY SHORE, NEW YORK.

DEVICE FOR SUSPENDING LIGHT-TRANSMITTING BOWLS.

1,228,969.

Specification of Letters Patent. Patented June 5, 1917.

Application filed February 17, 1917. Serial No. 149,157.

To all whom it may concern:

Be it known that I, JAMES T. ROBB, a subject of the King of Great Britain, residing at Bay Shore, in the county of Suffolk and State of New York, have invented an Improvement in Devices for Suspending Light-Transmitting Bowls, of which the following is a specification.

My invention relates to means for suspending a translucent bowl in electric lighting fixtures beneath and surrounding the lamp or lamps in order to provide for the indirect transmission of the light and to prevent injury to the eyes, which is liable to occur where powerful lamps are employed which transmit the light in a direct manner. In many fixtures of such character a shade or dome is employed above the lamps, and where a translucent bowl has been suspended below such shade or dome, it has been necessary to make holes in the shade or dome for the passage of the suspending chains or rods, and these apertures are frequently the cause of much damage to the glassware. One object of my present invention is to avoid the necessity for making holes in the shades or domes, thereby preventing injury to the glassware from such cause, and a further object of the invention is to provide means for so doing which is applicable to various styles of lighting fixtures at present in use without requiring any change whatever in such fixtures, and also allowing for the attachment of my device with great facility and without requiring the employment of any additional means to retain it in position.

The details of the invention are herein-after particularly described.

40 In the accompanying drawing:

Figure 1 is a plan of a blank showing my improved hanger cut out therefrom and before the arms are bent to position for use.

Fig. 2 is a plan view of the same after 45 the arms are bent to position.

Fig. 3 is an elevation of the same showing the chains attached.

Fig. 4 is an elevation showing the hanger in position upon a shade or dome, a portion 50 of the shade being broken away.

Fig. 5 is an elevation showing the hanger connected to a fixture and supporting a translucent bowl beneath the shade or dome, and

55 Fig. 6 is a similar view showing the

hanger connected to a different style of fixture.

Similar reference characters denote like parts throughout the several views.

10, indicates a flat ring provided with 60 spaced depending arms 11. While this ring and the arms may be cast or otherwise formed integral, the arms may be made separate from the ring and connected to it in any suitable manner, but I prefer to cut the 65 ring and arms out of a single piece of sheet metal as illustrated in Fig. 1 and afterward to bend the arms downwardly at right angles as shown in the remaining figures of the drawing. To the free end of each arm there 70 is connected in any suitable manner a chain 12. I have shown the arms as provided with a hole 13 for this purpose.

The other end of each of the chains 12 is provided with means for attachment to a 75 bowl; I have shown hooks 14 for making such connection.

15, indicates a shade or dome having the customary open neck 16 with flanged top.

The ring 10 is seated upon the top of the 80 neck of the bowl with the arms 11 extending downwardly within the neck and adjacent its sides, having the chains 12 attached, as most clearly illustrated in Fig. 4. It is then ready for connection with a fixture, and is 85 applicable to fixtures either provided with a shell or socket cover for connection with the shade or dome, or having a shade ring or holder into which the lamp socket is screwed. I have illustrated the first character 90 of fixture in Fig. 5, and the latter in Fig. 6.

In Fig. 5, 17 denotes the socket cover, and 18 a tube the threaded end of which connects with the top of the socket; the conductor wires (not shown) pass through the tube 18 to the lamp socket within the cover 17. An electric lamp 19, is shown in dotted lines.

The socket cover at its bottom has an annular rim 20, provided with spaced holes and threaded bushings 21, to receive the set-screws 22, which pass under the flanged rim of the shade or dome 15 and support it within the socket cover. 100

23, indicates a bowl of translucent material suspended beneath the shade or dome 15, by the chains 12.

As illustrated in this figure, the bowl 23, is provided with spaced holes 24, adjacent 110

its top into which the hooks 14 at the ends of the chains 12 are inserted.

In the style of fixture illustrated in Fig. 6, my improvement is connected in the same manner as in the fixture illustrated in Fig. 5, that is, the ring 10, is seated upon the top of the open neck of the shade or dome 25 with the arms 11, and chains 12, projecting downwardly within the shade or dome. The shade holder 26 is then placed over the ring 10, and secured to the shade by the set screws 27; the socket 28 is then screwed into the threaded opening in the holder 26, and the lamp 29 screwed into the socket. A translucent bowl may then be connected with the lower ends of the chains 12, as in the other instance.

This fixture may be hung from the ceiling by a chain 30 or connected with a tube or pipe as in the fixture illustrated in Fig. 5, which fixture may also be suspended by a chain if desired.

By the employment of my invention, the necessity for making holes in the shades or domes is entirely avoided. It may be connected with various fixtures already in common use with great facility and without

making any changes whatever in such fixtures, and without requiring any additional means for securing it in place. The ring has a uniform bearing upon the top of the neck of the shade or dome thereby avoiding any uneven strain upon the glassware, and is capable of supporting a very heavy bowl.

I claim as my invention:

In a lighting fixture and in combination, a shade having an open neck, a metal disk seated upon the top of said neck and having a central opening corresponding with the opening in the neck of the shade, said disk having integral spaced right angled projections extending through the neck of the shade, a lamp socket, a cover for the same fitting over said disk and surrounding the neck of the shade, means for securing said shade to the socket cover, chains each attached at one end to one of said projections at its free end, a bowl, and means connected to the lower end of each chain for connection with said bowl and for suspending the same beneath said shade.

Signed by me this 14th day of February, 1917.

JAMES T. ROBB.
